CLAIM

The ornamental design for a tool handle, as shown and described.

DESCRIPTION

FIG. 1 is a front perspective view of a tool handle according to the present design;

FIG. 2 is front elevation view of the tool handle of FIG. 1; FIG. 3 is a rear elevation view of the tool handle of FIG. 1; FIG. 4 is a left side view of the tool handle of FIG. 1; FIG. 5 is a right side view of the tool handle of FIG. 1; FIG. 6 is a top plan view of the tool handle of FIG. 1; FIG. 7 is a bottom plan view of the tool handle of FIG. 1; FIG. 8 is a cross-sectional view of the tool handle of FIG. 1 taken in the plane of and the direction indicated by line 8-8 of FIG. 2, with a cross-sectional view taken in the plane of and in an opposite direction indicated by line 8-8 being a mirror image thereof;

FIG. 9 is a cross-sectional view of the tool handle of FIG. 1 taken in the plane of and the direction indicated by line 9-9 of FIG. 2; and,

FIG. 10 is a cross-sectional view of the tool handle of FIG. 1 taken in the plane of and the direction indicated by line 10-10 of FIG. 2.

The broken lines in the drawings are for the purpose of illustrating portions of the tool handle that form no part of the claimed design. Surfaces forming part of the claimed design are defined by shaded surfaces; dash-dot lines represent boundaries of the claims and form no part thereof.
